PHOTO MOUNT

Carl A. Flood, Framingham, Mass., assignor to
Dennison Manufacturing Company, Framing-
ham, Mass., a corporation of Massachusetts

Application August 13, 1941, Serial No. 406,583

8 Claims. (Cl. 129—19)

This invention relates to mountings for photographs or the like, and more particularly to a hinged mounting for use in compiling a collection of photographs in overlapping series, to produce a neat and compact album.

Objects of the invention are to provide a hinged mounting which will permit a plurality of photographs to be mounted on any one page of an album, accurately define the hinge to thereby prevent any inadvertent off-center folding of the leaves, guard against lateral swinging of the mounted photograph as it is pivoted on the hinge, with resultant loosening of the mount from either the album page or the mounted photograph, furnish a convenient writing surface for the title, date or other memoranda pertaining to the photograph, permit of easy packing and handling as it remains flat until used, and which is generally superior in strength and efficiency to photograph mountings of the prior art.

Other and further objects and advantages of the invention will be pointed out hereinafter in the following more detailed description and by reference to the annexed drawing, showing for the purpose of illustration typical embodiments of the invention:

Fig. 1 is a front elevation of one embodiment of my invention showing a supporting surface carrying a plurality of photographs, the top photograph being turned upwardly to show the method of mounting by the use of this embodiment;

Fig. 2 is a side elevation of Fig. 1 showing only one of the photographs mounted on the supporting surface;

Fig. 3 is an enlarged side elevation of the embodiment shown in Fig. 2 before it is attached to the supporting surface and photograph;

Fig. 4 is an enlarged front elevation of Fig. 3;

Fig. 5 is a front elevation of another embodiment of my invention showing a supporting surface carrying a photograph and showing the method of mounting by the use of this embodiment;

Fig. 6 is an enlarged side elevation of Fig. 5;

Fig. 7 is an enlarged side elevation of the embodiment shown in Fig. 6 before it is attached to the supporting surface and photograph; and

Fig. 8 is an enlarged front elevation of Fig. 7.

Referring to the drawing, the particular embodiment of the mount shown in Figs. 1 to 4 comprises an elongate blank 1 of flexible sheet material, as cloth, paper, or the like, comprising two leaves 2 and 3 and an intermediate hinge 4. The rear faces 5 and 6 of leaves 2 and 3 are coated with a suitable adhesive which preferably covers their entire surfaces. The adhesive to be used may be of any suitable type including, but not by way of limitation, water-remoistenable

gumming, thermoplastic coatings or pressure sensitive adhesive which may be temporarily covered with paper or the like which, when the mount is to be used for its intended purpose, is readily stripped off exposing the adhesively coated areas. The leaf 3, which is to be attached to a supporting surface 7, such as the page of an album, may be slightly wider than leaf 2.

Stiffening means comprising reinforcing strips 8 and 9 are superimposed on the front faces 10 and 11 of leaves 2 and 3 by suitable means, as adhesive, the inner edges of said strips 8 and 9 extending approximately medially of the elongate blank 1 and being spaced apart slightly to define the intermediate hinge 4. Said reinforcing strips 8 and 9 further provide a writing surface upon which memoranda pertaining to the photograph may be made to appear. While preferably in the form of strips 8 and 9 some of the advantages of the present invention may be obtained by using coatings of shellac, varnish, lacquer, starch or similar materials as the reinforcing means.

In the use of a photograph mounted as disclosed in the above embodiment, leaf 3 is fastened to the supporting surface 7 by moistening the adhesive on the rear face 6 thereof and applying it to said supporting surface 7. Leaf 2 is then swung forwardly on the hinge 4 until it overlies leaf 3, exposing its adhesively coated face 5. Said adhesively coated face 5 is then moistened and the top margin of the rear of a photograph 12 is applied thereto. The photograph is then swung upwardly upon the mount and memoranda pertaining thereto may be written upon the reinforcing strips 8 and 9, which are normally concealed beneath said photograph 12, as shown in Fig. 2. While the picture 12 is in its upwardly swung position, other photographs may be mounted in the above-described manner and in overlapping series. After the desired number of photographs have been so mounted and marked, they are swung downwardly on the hinges 4 to assume their normal position, as shown in Fig. 1.

The preferred embodiment of my invention shown in Figs. 5 to 8 comprises an elongate blank 1 of flexible sheet material, similar to that shown in Figs. 1 to 4 in that it has like leaves 2 and 3 and an intermediate hinge 4, but as shown in Fig. 7 the adhesive is applied to the rear face 5^a of leaf 2 and the front face 11^a of leaf 3. The leaf 2, which is to be attached to the supporting surface 7, may be slightly wider than leaf 3.

Stiffening means comprising reinforcing strips 8^a and 9^a are preferably superimposed, as shown in Figs. 6 and 7, on the front face 10^a on leaf 2 and on the rear face 6^a of leaf 3 by suitable adhesive means, the inner edges of said strips 8^a and 9^a similarly extending approximately me-

dially of the elongate blank 1 and being similarly spaced apart slightly to define the intermediate hinge 4. In this preferred form the reinforcing strip 8^a preferably provides a writing surface upon which memoranda pertaining to the photograph may be made to appear (Fig. 8).

In the use of the preferred embodiment above described, leaf 2 is fastened to the supporting surface 7 by moistening the adhesive on the rear face 5^a thereof and applying it to said supporting surface 7 as shown in Fig. 6. The adhesively coated face 11^a of leaf 3 is disposed in the position shown in Figs. 6 and 7 and is ready to be attached to the top margin of the rear of the photograph 12 by moistening and applying it thereto. The memoranda pertaining to this photograph may be then written upon the unconcealed reinforcing strip 8^a of leaf 2, as shown in Fig. 5. The photograph 12 may then be swung upwardly on hinge 4 to permit the mounting of additional photographs in the manner above described and in overlapping series, after which all photographs are swung downwardly into the position shown in Fig. 5.

It is to be noted that in each of the disclosed embodiments the hinge is defined by the inner edges of the reinforcing strips, thereby assuring perfect alignment of the vertical edges of leaves 2 and 3 when they are folded about hinge 4, with the resultant perfect alignment of the vertical edges of the mounted picture with the vertical edges of the supporting surface or album page. It is further to be noted that the reinforcing strips also prevent lateral swinging of the photograph when it is either upwardly or downwardly swung, with consequent avoidance of the loosening of the mount from either the supporting structure or the mounted photograph.

It should be understood that the present disclosure is for the purpose of illustration only and that this invention includes all modifications and equivalents which fall within the scope of the appended claims.

I claim:

1. In a device of the class described the combination of a graphic display, a supporting surface therefor, a mount for hinging the display on said surface, the mount having leaves with faces cemented to the display and surface respectively and an intermediate flexible hinge about which the display and its leaf may swing relatively to said surface and the other leaf, one of said leaves having a stiffening sheet cemented to its free face to prevent its first-named face from pulling loose adjacent said hinge as the display is swung back and forth.

2. In a device of the class described the combination of a graphic display, a supporting surface therefor, a mount for hinging the display on said surface, the mount having leaves with faces cemented to the display and surface respectively and an intermediate flexible hinge about which the display and its leaf may swing relatively to said surface and the other leaf, one of said leaves having a stiffening sheet of writing paper cemented to its free face to prevent its first-named face from pulling loose adjacent said hinge as the display is swung back and forth and to receive descriptive indicia.

3. In a device of the class described the combination of a graphic display, a supporting surface therefor, a mount for hinging the display

on said surface, the mount having leaves with faces cemented to the display and surface respectively and an intermediate flexible hinge about which the display and its leaf may swing relatively to said surface and the other leaf, said leaves having stiffening sheets cemented to their free faces to prevent said first-named faces from pulling loose from the display and surfaces respectively as the display is swung back and forth.

4. In a photographic display device of the type in which a photographic display is hingedly affixed to a support so that said display may be freely swung back and forth, a mount comprising leaves each having an adhesive coated surface on one face for attachment to the display and support respectively, an intermediate flexible hinge about which the leaves may be folded, and at least one leaf having superimposed means on its opposite face for preventing the leaf from pulling loose from its attachment as the display is swung back and forth.

5. In a photographic display device of the type in which a photographic display is hingedly affixed to a support so that said display may be freely swung back and forth, a mount comprising leaves each having an adhesive coated surface on one face for attachment to the display and support respectively and provided on its opposite face with a reinforcing strip for preventing said leaves from pulling loose from the display and support as the display is swung back and forth and for defining a flexible hinge between the leaves.

6. In a photographic display device of the type in which a photographic display is hingedly affixed to a support so that said display may be freely swung back and forth, a mount comprising leaves each having an adhesive coated surface on one face for attachment to the display and support respectively and provided on its opposite face with a reinforcing strip for preventing said leaves from pulling loose from the display and support as the display is swung back and forth and for defining a flexible hinge between the leaves, at least one of said reinforcing strips providing a readily exposable smooth writing surface.

7. In a photographic display device of the type in which a photographic display is hingedly affixed to a support so that said display may be freely swung back and forth, a mount comprising leaves, the front of one leaf and the back of the other having an adhesive coated surface for attachment to the display and support respectively, and stiffening means on the face of each leaf opposite its attaching surface for defining a flexible hinge about which said leaves may be folded and for preventing said leaves from pulling loose from the display and support as the display is swung back and forth.

8. In a photographic display device of the type in which a photographic display is hingedly affixed to a support so that said display may be freely swung back and forth, a mount comprising an elongate strip of sheet material having upper and lower sections coextensive with its length and having an adhesive coated surface on the upper and lower sections of one face for attachment to the display and photograph respectively, and a reinforcing strip superimposed on at least one section of the opposite face for preventing the section from pulling loose from its attachment as the display is swung back and forth.

CARL A. FLOOD.
